METHOD OF FURNACE OPERATION

Norman J. Urquhart, Scenery Hill, Pa., assignor
to Steel Processing Company, Pittsburgh, Pa.,
a corporation of Pennsylvania

Application December 20, 1946, Serial No. 717,509

4 Claims. (Cl. 263—52)

1 This invention relates to a method of furnace operation and relates particularly to a method of operating a metallurgical furnace for heating solid bodies of metal such as steel ingots, iron and steel castings, blocks and other bodies of iron and steel in a heat-treatment or in preparation for mechanical working.

To consider initially some problems involved in the heating of solid metal bodies, it should be considered that the fundamental heat-absorbing and temperature-attaining properties of a metal body depend upon several factors. One such factor is the metal of which the body is composed including the relative purity of such metal or the alloy or composition of which it is composed, and in such connection the carbon content of steel may be considered to be of particular importance. Each metal and metal alloy or composition has its own particular properties with respect to heat absorption and conductivity and conversely its resistance to heat absorption and conduction. The mass and shape of the body is a factor in determining the rate of heat absorption and heat conduction within the body required to bring it uniformly to a desired temperature. There are serious problems involved in supplying an overall heat-input to a metal body in a manner to obtain satisfactory equalized heating to the desired temperature. Because of the variety of factors involved and for other reasons it has been impractical to plot and accurately to follow a heating curve for each particular furnace charge.

It is of primary importance to bring the interior structure of a charge body to the desired temperature without raising its temperature regionally, as at any portion of its surface, to a point at which the metal becomes fluid. The greatest difficulty in this connection is encountered in heating packs of sheets or plates in which heat must be conducted from the surface of the pack to its interior regions. Great difficulty has been encountered in raising such composite bodies to an equalized high temperature without producing welding between the sheets or plates in some region of the pack. In an annealing operation performed on material of that sort the greatest care previously exercised frequently is inadequate at all stages of the operation to limit the input of heat to the furnace charge below that at which component elements of the pack become regionally heated to a welding temperature.

In metallurgical heating operations as previously performed it has been impractical to ob-

2 tain indication of the internal temperature of an ingot, block, sheet pack or other body of the metal at various stages of the heating operation in such manner as to guide controlled furnace operation. It also has been difficult and frequently has been found impossible so to control the heat-input to a furnace chamber during all stages of a heating operation that the bodies of metal comprised in the furnace charge attain each its desired equalized high temperature without regional overheating.

It is a primary object of my invention to provide a method of furnace operation which gives indication as to the internal temperature of the metal bodies being heated during the progress of the operation and which provides combustion of such sort and under such control that heat absorption by the bodies of the furnace charge is facilitated and the heating is effected in a manner to equalize the temperature throughout the structure of the bodies, without localized overheating of the bodies at any stage of the furnace operation.

Other objects of my invention are to provide a method of furnace operation of such sort that the furnace chamber and furnace charge may be raised to a desired temperature while avoiding substantial combustion against the walls of the furnace chamber and the furnace charge; to provide a method which gives in the furnace chamber a furnace atmosphere of high heating value; and to effect the purpose of the heating operation with economy in fuel as well as in advantageous manner with respect to the effect of such operation on the furnace charge.

Another object of my invention is to obtain the above advantages while utilizing a furnace having such simplicity in structure that installation costs are minimized and overall production is promoted by economy in the floor space occupied by the furnace installation.

Whereas the utility of my method of furnace operation which is emphasized herein relates to the heating of metal bodies in metallurgical practice, the invention as will be explained has various other important applications. Briefly and generally stated with respect to the operation of a charged metallurgical furnace, my method consists in sealing the furnace chamber in a manner to provide an inlet for burner products and an outlet orifice for products of combustion. The burner products are supplied directly to a furnace chamber under positive pressure created by the operation of the burner, and desirably are introduced by way of a combus-

tion tunnel. Such burner products are in approximately stable condition and form an approximately stable mixture when they enter the furnace chamber. Products of combustion from the furnace chamber are discharged against atmospheric pressure, without the creation of negative pressure or "pull" outwardly of said orifice. The area of the outlet orifice from the furnace being adjusted to the particular operation which is contemplated, normally remains constant during at least the major part of that operation. Combustion is so largely performed before the burner products enter the furnace chamber that the furnace atmosphere as well as the furnace pressure is directly under burner control and the firing is both direct and economical.

The furnace chamber being maintained throughout the furnace operation under a positive pressure created by burner operation, such positive pressure is directly under burner control and normally varies in value directly with the volume of burner products introduced to the furnace chamber. The furnace atmosphere in the metallurgical heating desirably comprises luminous carbon particles which intensify heat transfer within the furnace chamber. The furnace atmosphere remains stable throughout the entire range of burner input, so that burner control can be used to vary at will the volume of burner products with control of quantitative heat-input or the temperature of burner products without in either instance departing from the desired atmospheric conditions in the furnace chamber.

To give a theoretical background, serving to clarify essential features of my method, it should be understood that with combustion of the sort which has been described a selectivity or relativity in the heating and in the temperature conditions of the furnace chamber and the work is obtainable. Let it be assumed that the furnace chamber is empty, and that by burner operation the atmosphere in the furnace chamber is brought to a desired temperature. When that temperature has been obtained, it is maintainable merely by a heat-input sufficient to compensate for the "shed" of the furnace at that temperature; that is, to compensate for heat loss to the outer atmosphere. If then we assume that a cold charge is introduced, the rate of heat-input being unaltered, the furnace temperature of course drops. Given a long period of furnace operation, however, both the furnace chamber and the charge will again be brought uniformly to the initially selected temperature.

This apparently contradictory circumstance stems from the fact that the charge receives heat directly from the combustion atmosphere which is created by the burner and not by radiation from the interior of the furnace walls. Thus the bodies of the charge are preferentially heated with respect to heat loss through the physical structure of the furnace, so that the charge as well as the furnace atmosphere must be brought to the initial temperature before the "shed" arrives at its initial value. At this point a recording thermometer will indicate continuing uniformity in the furnace temperature. These results rising from preferential heating of the charge in a suitable combustion atmosphere lead not only to fuel economy, but also as a matter of far greater importance form the basis for observing the internal temperature conditions of the charge body and for effecting accurate con-

trol of conditions in the furnace chamber and in the charge.

It should be understood, however, that it would be uneconomical in furnace time to conduct an entire heating operation at such "low-fire," that is under a heat-input based on the "shed" of the furnace at the temperature to which the charge is to be brought. In practice I therefore control the burner input between such low input and a higher heat-additive burner input, to accelerate the rate of heat supply to the furnace charge. Under optimum conditions, the heat-additive input is effected at "high-fire" or at "extra-high-fire." The terms "high-fire" and "extra-high-fire" may be defined respectively as: (a) the rate of heat-input which will most economically supply heat to relatively hot work at its maximum rate of heat absorption in that temperature range, and (b) the rate of heat-input which will most economically supply heat to relatively cold work at its maximum rate of heat absorption in that temperature range.

It should be understood that the terms "high-fire" and "extra-high-fire" express optimum heat-additive burner operation and that departure from such conditions is possible, provided heat-input is not so excessive that any region of a charge body reaches a melting or welding temperature. Similarly, the optimum heat-input at "low-fire" not only is based on the "shed" of the furnace at the desired final temperature of the charge but involves a control very closely to neutralize that heat loss. Some variation from exactitude in this respect is, however, permissible.

With the understanding that the method of my invention may be practiced in furnaces of widely varying types, the accompanying drawings are illustrative of one apparatus, or installation, embodiment suitable for the performance of my method. In the accompanying drawings:

Fig. I is a vertical sectional view through a furnace suitable for the performance of my method, which is organized as a soaking pit.

Fig. II is a schematic plan view of a complete installation including the soaking pit and various control elements suitably used with it in the performance of the method.

Fig. III is a schematic diagram illustrating electrical connections for automatically operating a furnace in accordance with the method of my invention.

Fig. IV is a graphic illustration of the control of the valve-operating motors under the influence of two sequentially effective thermocouples.

Referring initially to Fig. I of the drawings, reference numeral 1 designates generally a furnace having therein a furnace chamber 2 closed at its upper end by a cover 3, which desirably has an air tight setting on the walls 4 of the furnace provided in suitable manner as by a sand seal 5. As shown, the furnace charge consists of a plurality of ingots A which stand upon the usual loose heat-insulating bottom 6 provided at the base of the furnace. The outlet orifice from the furnace is provided by a discharge port 7 of fixed dimensions which is shown as located at a low level in one wall of the furnace and a refractory duct 8 which leads to a short stack 9. In refractory duct 8 there is an adjustable gate 10 which is used to regulate the area of the outlet orifice and consequently to regulate pressure within the furnace chamber in accordance with the conditions of each particular furnace operation. As above indicated, this adjustment is

performed prior to the furnace operation and normally is not changed during the operation, being set to give positive pressure in the furnace chamber at the lowest burner input employed during the operation.

In Fig. I an inlet port 11 is shown as positioned in the upper region of the same wall through which outlet port 7 leads. This inlet port 11 is as shown so dimensioned that it forms all or part of a combustion tunnel which is effectively a part of a burner 12. Burner 12 with its combustion tunnel is a burner of such sort that it is capable of providing and introducing into the furnace chamber under the pressure of the burner a mixture of burner products which because of conditions in the burner and the stage to which combustion proceeds in the tunnel is approximately stable and uniform; and which mixture of burner products on entry into the furnace chamber gives therein a luminous unstratified furnace atmosphere. Such burner is typified, as shown, by a burner in accordance with the disclosure of my application Serial No. 563,684, which has matured into Patent No. 2,458,541, granted January 11, 1949. As shown furnace 1 is equipped with two thermo-couples 13 and 14 mounted in opposite walls 4 of the furnace. Of these two thermo-couples, thermo-couple 13 is placed at a high level of the furnace and thermo-couple 14 at the low level thereof.

In the furnace operation, a stable mixture of burner products is introduced into the upper region of chamber 2 under positive burner pressure and at a temperature of those products somewhat above the temperature to which the charge ultimately is to be raised. The pressure in furnace chamber 2 thus builds up to a degree determined by the setting of damper 10, and after circulating through the furnace chamber products of combustion are discharged under the positive pressure which has been established in the furnace chamber. It is to be understood that the relatively low stack 9 does not create any substantial draft, to place the outlet orifice and the furnace chamber under the pull of a negative pressure. Because the area of the outlet orifice from the furnace chamber remains constant as pressure builds up under the burner input, the positive pressure in the furnace chamber increases in value with increased input volume of the burner products, thus insuring combustion of the desired kind and good heat distribution in the furnace chamber. At low burner input any relief of pressure by increasing the area of the outlet orifice would destroy the calculations based on the furnace "shed" and thus would destroy the basis for controlling the furnace operation. It is only at high pressure build-up under high burner input that any substantial pressure relief may be made during the operation of the furnace without impairing seriously the effectiveness of the operation.

Assuming that the furnace is to be charged with metal bodies such as the steel ingots shown in Fig. I, damper gate 9 is adjusted to maintain positive pressure in the furnace chamber during the heating operation and the empty chamber is brought to the temperature to which the charge uniformly is to be raised. On introduction of the furnace charge the temperature drops and the burner is controlled to give a definitely heat-additive input. Desirably this heat-input is the "extra-high-fire" noted above, which gives the maximum heat supply to the furnace charge without raising any region of the charge to a de-

structive temperature and without producing excessive heat loss through the physical structure of the furnace. Such optimum temperature for supplying heat to a cold charge is roughly determinable in accordance with known calculations in accordance with the total mass of the charge and the mass and composition of the body or bodies of which the charge is composed, but is subject to control in accordance with direct observation by way of thermo-couple 13 which is to be considered as the primary couple. When the thermometer connected with primary couple 13 tends to show increase in temperature indicating that the rate of heat-input exceeds the absorption rate by the charge, the burner input is cut down to "low-fire" which is based on the heat shed of the furnace at the desired ultimate temperature of the work. Under this heat-input there is heat flow within the bodies of the ingots tending to bring the less directly heated regions of those bodies closer to the temperature of their more directly heated regions. As this action proceeds and the structure of the ingots proceeds toward temperature equalization there is a drop in furnace temperature, and when this drop becomes substantial the higher burner input is again restored.

The cycle is repeated, first dropping heat-input to "low-fire" and then restoring it to "extra-high-fire" until the drop in temperature on the control to "low-fire" begins definitely to lag, showing that the centers and lower regions of the ingots have reached such temperature that the rate of heat transfer within and to the charge is greatly reduced. Because burner products are shown as introduced at the upper region of the furnace chamber, heat is received more directly by the upper regions of the ingots than by their lower regions. When the heating operation has reached the above indicated stage the lower thermo-couple 14 which is the secondary couple will cause its thermometer to indicate a selected temperature which is below but approaching the highest desired temperature shown by the thermometer of the primary couple. Burner operation then is controlled between the heat-input of "low-fire" and the heat-input of "high-fire" which latter is according to the definition which has been given a safe and economical heat-input for a charge which is already at relatively high temperature. The cycle is continued between "low-fire" and "high-fire" until the thermometer associated with the secondary thermo-couple records a line closely approaching that scribed by the thermometer of the primary thermo-couple. The heating operation is then to be considered as completed, with the charge fully heat-soaked to the desired temperature equalized throughout each body of the charge.

Positive information that the temperature of a metal body comprised in the furnace charge is of equalized temperature throughout its structure is an important advantage. Particularly is this the case when the work or furnace charge consists of light sheets made into a pack, or such other laminated structure that the danger of welding between the elements of the pack is a matter of primary importance. It is a simple matter to determine in such instance at what temperature welding will occur. It is a difficult matter, however, to effect heating with temperature equalization throughout the entire structure of the pack without raising any region of it to that welding temperature.

As above noted, the indication of internal

temperature is obtained by basing the low burner input on that rate of heat-input which will just compensate for normal furnace losses at a given temperature. Under such conditions the only factor to affect the temperature of the furnace chamber is the charge itself; and if a temperature gradient in any direction exists in the work, the resulting heat-flow to and from the furnace atmosphere will be indicated as either a rise in temperature or fall in temperature, on the recording thermometer. If on the contrary there is no temperature change registered by the recording thermometer, it follows that there is no temperature gradient within the structure of the charge bodies, and that the center of such bodies is at the same temperature as their outer structure. The result is that the control of heat-input and termination of the heating operation is definitely in accordance with indications given by the furnace charge itself and does not depend upon arbitrary precalculation. With reference particularly to the selective use of "high-fire" and "extra-high-fire" it will be understood that such distinction is based on the fact that metal can absorb heat much faster when it is cold than when it is hot and it is therefore both safe and economical to employ a higher heat-additive burner input in beginning the heating operation than when that operation is nearing its conclusion.

As above described, the method of my invention places the control of the heating operation under the direction of the furnace charge. Furnace conditions are as has been explained directly under the control of the burner or burners of the furnace installation. By the use of automatic equipment the heating operation may be placed directly under control of the furnace charge, by utilizing instruments influenced by the condition of the work as above explained to control the burner or burners of the furnace.

A complete furnace installation arranged for automatic regulation is shown schematically in Fig. II of the drawings. In Fig. II the furnace and such of its associated elements as are shown in Fig. I are designated by the same reference numerals. Additionally, however, Fig. II shows a fuel line 15 leading from a source of fuel supply to burner 12 by way of a ratio control 16 and a low velocity air line 17, which receives air under pressure from a constant pressure blower 18 and which also leads to burner 12 by way of ratio control 16. Ratio control 16 desirably has associated with it a regulating relief attachment such as that disclosed in my Patent No. 2,408,114 to give ultimate adjustment between fuel and air in accordance with the atmosphere in furnace 1. A high pressure air line 19 also leads to burner 12, to provide a fuel-carrying and fuel-filming jet therein.

Both recording thermometers connected respectively with primary thermo-couple 13 and secondary thermo-couple 14 are incorporated in a controlling potentiometer 20 comprising relays which will act at set temperatures to control the action of a motor 21 which operates to open and close fuel and air valves of the ratio control 16. As shown circuits 22 and 23 lead from the two thermo-couples to the recording and controlling potentiometer 20.

In automatic control the primary thermo-couple 13 acts on potentiometer relays, the contacts of which may be set to open and close at determined temperatures. Following the cycle of the operation as described above with refer-

ence to the automatic equipment it will be assumed that as described the initial action is under control by the high or primary thermo-couple 13. The potentiometer controller contacts are set to control burner input to a temperature of the furnace chamber at "extra-high-fire" and at "low-fire." When the temperature in the furnace chamber tends to exceed the temperature of "extra-high-fire," the potentiometer controller automatically acts through electrical connections 24 to cause motor 21 so to act on the valves of ratio control 16 that the burner input is reduced to a "low-fire" value. When heat transfer within the bodies of the charge has taken place and the furnace temperature drops below the temperature point at which the contacts of its relays are set the potentiometer controller acts through motor 21 on the valves of the ratio control box to restore the burner input to "extra-high-fire"; and as above described this cycle is repeated automatically with the burner controlling combustion conditions in the furnace and the condition of the charge as reflected by furnace conditions controlling the operation of the burner.

The above described cycle continues until the temperature recorded by the thermometer associated with the secondary thermo-couple 14 reaches a predetermined point which is below the highest point at which the contacts associated with the primary thermo-couple are set. When the thermometer of the secondary couple reaches that point, the potentiometer controller acts to introduce a limit switch into the circuit of motor 21. That limit switch acts so to limit the action of the motor that the motor stops short of producing complete opening of the valves of the ratio control, the limiting point being such as to give a burner input responding to the input at "high-fire" which has been described above. The burner is then controlled alternately between "high-fire" and "low-fire" during the remainder of the heating operation, the burner input at the higher heat-additive point being such as to insure against injury to the furnace charge because of excessive heat-input at the temperature to which the charge has been brought. The cycle is continued under such conditions until a condition of the furnace charge is reached at which the line recorded by the secondary thermo-couple 14 closely approaches the line scribed by the primary thermo-couple 13. At that temperature the bodies of which the charge is composed are assumed to have been equalized throughout their structure at the ultimate desired temperature and the heating operation is assumed to have been completed.

Fig. III of the drawings shows an electrical circuit for effecting automatic energization of the valve motor to produce the above described sequence of steps. The circuit is shown by means of what might be called a schematic diagram which omits the symbols for relays, motors and the like.

R_1 is a manually-operable general control switch. H_1 , H_2 , L_1 , L_2 and H_3 are snap contacts which operate under the influence of temperature. The interrupters INT_1 and INT_2 are motor driven and introduce a time element. Contacts L_1 , L_2 and L_3 like contacts H are snap contacts. All the L contacts give high fuel supply under low temperature conditions; all the H contacts give low fuel supply under high temperature conditions. Interrupter INT_1 acts to close in balance

of the couple 13; interrupter INT₂ closes in balance of the couple 14.

At the beginning of the operation all the H contacts are open and all the L contacts are closed. L₁ opens up causing the valve mechanism to admit a low flow of fuel. Then H₁ closes to give an alternating provision of fuel flow for "extra high fire" and fuel flow for "low fire", by the making and breaking of contacts L₁ and H₁ under the timed interruptions of interrupters INT₁. This action continues until contact H₃ makes its contact at the control point of thermo-couple 14. Relay R is thus energized opening contact R₂ to bring SL limit switch into the circuit. H₂ contacts then make, causing the valve mechanism to shift to low fuel input. On actuation of the valve caused by drop in temperature the valve mechanism opens into a position determined by the setting of limit switch SL to give a fuel input for "high fire". The action then is between "low fire" and "high fire" for the duration of the heating, by the making and breaking of contacts L₂ and H₂ under the timed interruptions of interrupters INT₂. When the interruptions by interrupters INT₂ fail to produce a substantial temperature drop during the timed period of the interruption, contacts H₂ remain closed and fuel flow remains at "low fire".

To give a safety factor if there should be a temporary failure of the furnace burner or if for any other reason the temperature should drop to a determined limit below the control point of thermo-couple 41, contacts L₈ make to bring "extra high fire" again into existence, switch SL being by-passed.

This described circuit as herein shown is a modification of a standard Leeds & Northrup circuit.

It may be explained in connection with the above, that the designation of the higher thermo-couple as the primary thermo-couple and the designation of the lower thermo-couple as the secondary thermo-couple is based upon the organization of the particular furnace structure which is illustratively used. The designation rises from the fact that burner products are introduced into that furnace in an upper region of the furnace, so that the portion of the furnace charge which extends into that region receives the most direct heating effect. The secondary thermo-couple is placed in a region of the furnace at which the heating effect is less direct, so that the portion of each body lying in that region tends to remain at a lower temperature than the portion of the body which extends into the upper region of the furnace. The distinction is therefore between the relative tendencies toward the acquisition of high temperature regionally of the charge bodies, and there must be heat flow within the substance of those bodies from the most directly heated regions thereof to their less directly heated regions if they are to attain equalized temperature. If the furnace were to be so arranged that burner products are introduced in a lower region of the furnace, the position of the primary and secondary thermo-couples would be reversed. Also it should be explained that although the furnace illustrating the performance of my method is shown as having a single burner-equipped inlet and a single outlet, a plurality of either or both may in some instances desirably be incorporated in the furnace structure.

It should be explained that whereas I believe

the disclosed arrangement of automatic electric equipment to control burner input to a furnace to be novel, the automatic electric elements, the presence and function of which have been described are in themselves of well known sort commercially available as independent units of automatic electric equipment.

It has been indicated above that whereas my method has been described with particular reference to a heating operation conducted in a metallurgical furnace, the method usefully may be performed in utilizing a heating furnace on work of variant sort. Thus, for example, the furnace charge may be ceramic material, a bath of glass, preformed glass bodies subjected to an annealing operation or a steam-generating furnace. In such latter use the charge is represented by the structure which contains the water from which steam is to be generated and that water itself. In all such operations the controlled input of burner products and the observation and control of conditions in the furnace and its charge give definite advantage in obtaining an equalized heating of the furnace charge to a desired temperature, without localized or general overheating and with economy in fuel consumption.

Further, it should be borne in mind that in any specific use of my method control of heat and temperature and temperature equalization is obtained by direct as opposed to indirect firing of the furnace. Also it should be borne in mind that with the disclosed type of combustion and control of furnace atmosphere conditions, check-work and recuperators are eliminated; thus decreasing construction costs and lessening the floor space required for the furnace installation.

I claim as my invention:

1. The method of operating a charged metallurgical furnace to raise the temperature of a metal body therein uniformly to a desired degree, by introducing directly into the furnace chamber an approximately stable mixture of burner products moving at low velocity and under positive burner pressure, discharging products of combustion from the furnace chamber by way of an outlet orifice of constant area under a positive pressure in said furnace chamber, and automatically controlling the heating of the furnace charge to a determined equalized temperature in accordance with the temperature in a high temperature zone of the furnace under alternating conditions of low input based on furnace losses at the determined equalized temperature for the charge and a higher heat-additive input volume, with consequent heat flow within the body of the charge at said low input until the determined equalized temperature of the charge is maintained under the conditions of low burner input.
2. The method of operating a charged metallurgical furnace to raise the temperature of an initially relatively cold body therein uniformly to a desired degree by directly introducing into the furnace chamber an approximately stable mixture of burner products moving at low velocity and under positive burner pressure, discharging products of combustion from the furnace chamber by way of an outlet orifice of constant area under a positive pressure in the said furnace chamber, initially controlling the heating of the furnace charge in accordance with the temperature in a high temperature zone of the furnace with alternation between a higher heat supply to the furnace charge which is the approximate maximum possible without raising any region of the relatively cold charge to a destructive tem-

11

perature and a low heat supply based on furnace losses at a determined equalized temperature for the charge with consequent heat flow within the body of the charge until the drop in temperature upon shift to low heat supply begins to lag, then shifting to control of heating in accordance with the temperature in a low temperature zone of the furnace with alternation of heat supply to the furnace charge between a heat supply which is the approximate maximum without raising any region of the hot charge to a destructive temperature and the said above defined low heat supply until no substantial temperature drop occurs upon shifting from higher heat supply to the said above defined low heat supply.

3. The method of operating a charged metallurgical furnace to raise the temperature of an initially relatively cold body therein uniformly to a desired degree by directly introducing into the furnace chamber an approximately stable mixture of burner products moving at low velocity and under positive burner pressure, discharging products of combustion from the furnace chamber by way of an outlet orifice of constant area under a positive pressure in the same furnace chamber, initially controlling the heat of the furnace charge automatically in accordance with the temperature in a high temperature zone of the furnace with alternation between a higher heat supply to the furnace charge which is the approximate maximum possible without raising any region of the relatively cold charge to a destructive temperature and a low heat supply based on furnace losses at a determined equalized temperature for the charge with consequent heat flow within the body of the charge until the drop in temperature upon shift to low heat supply begins to lag, then automatically shifting to control of heating in accordance with the temperature in a low temperature zone of the furnace with automatic alternation of heat supply to the furnace charge between a heat supply which is the approximate maximum without raising any region of the hot charge to a destructive temperature and the said above defined low heat supply until no substantial temperature drop occurs upon shifting from higher heat supply to the said above defined low heat supply.

12

4. The method of operating a charged metallurgical furnace to raise the temperature of a metal body therein uniformly to a desired degree, by directly introducing into the furnace chamber 5 an approximately stable mixture of burner products moving at low velocity and under positive burner pressure, discharging products of combustion from the furnace chamber by way of an outlet orifice of constant area under a positive pressure in said furnace chamber, automatically 10 controlling the heating of the furnace charge to a determined equalized temperature in accordance with the temperature in a high temperature zone of the furnace under alternating conditions of low input based on furnace losses at the determined equalized temperature for the charge and a higher heat-additive input volume, with consequent heat flow within the body of the charge at said low input until the determined equalized 15 temperature of the charge is maintained under the conditions of low burner input, and holding in the furnace chamber a positive pressure of a value varying throughout at least the major portion of the furnace operation directly with the 20 volume of burner input.
